UNITED STATES PATENT OFFICE.

FRANK M. FLOYD, OF DALLAS, TEXAS.

APPARATUS FOR REFINING HYDROCARBON MATERIALS.

Application filed May 19, 1922. Serial No. 562,135.

This invention relates to an improved apparatus for the refining of hydrocarbon materials.

An object of this invention is the provision of an apparatus for the treatment of hydrocarbon materials, so designed as to permit of a continuous process capable of operating over a relatively long period of time without injury or deterioration to any 10 of the individual units of said apparatus.

A further object of the invention is the provision of a refining apparatus of the above mentioned character, including an improved distilling chamber having the bottom thereof so protected from the liability of carbon deposits that the same may be operated for a relatively long period of time.

A further and important object of this invention is the provision of a novel type of 20 reflux condenser designed to handle unheated supplies of hydrocarbon products for initial treatment by the heated hydrocarbon vapors passing therethrough; said vapors and the unheated hydrocarbon liquid being 25 so separated as to prevent any liability of the association of the ingredients of one with the ingredients of the other.

A further object of the invention is the provision of an improved refining apparatus designed from a practical and economical standpoint to produce a relatively great yield of the more volatile fraction of 30 a hydrocarbon material.

Other objects and advantages will be apparent during the course of the following detailed description.

In the accompanying drawing, forming a 40 part of this specification, and wherein similar reference characters designate corresponding parts throughout the several views,

Figure 1 is a side elevation of the improved apparatus showing parts thereof in section.

Figure 2 is a transverse cross sectional view taken through a still embodied in the improved apparatus.

Figure 3 is an enlarged fragmentary view, taken substantially on the line 3-3 of Figure 2.

Figure 4 is an enlarged fragmentary sectional view, showing the manner in which several parts of the still are cooperatively positioned.

Figure 5 is a transverse cross sectional

view taken through a reflux condenser and showing the cooperating parts thereof.

In the drawings, wherein for the purpose of illustration is shown the preferred embodiment of this invention, the letter A generally designates the apparatus including a still B; furnace C; reflux condenser D; condenser E; gas separator F; receiving tank G; gas storage tank H; and cooling container K.

The still B is preferably of the horizontal cylindrical type supported above the fire box 10 of the furnace C. Crude petroleum or the desired hydro-carbon material is initially supplied to the chamber 11 of the still B through a charging line 12; said hydro-carbon material being forced through the line 12 as by a pump 13. A meter 14 may be connected in the line 12 to determine the volume of hydro-carbon liquid passing into the chamber 11. A cut off valve 15 is preferably positioned in the charging line 12 for regulating the initial flow of hydrocarbon material into the chamber 11. The ordinary accessories may be mounted upon the still B, such as man holes 17 provided in the forward and rear end plates 18 and 19 of the still B. A pressure gauge 20 may be provided in the forward plate 18, as may also a temperature gauge 21.

It is well known to those skilled in the art to which this invention pertains that the still B in which destructive distillation takes place can be operated but a short length of time, due to the fact that carbon deposits settle in the chamber 11 upon the bottom of still B, and form a caked mass, which becomes over-heated, so that the heat units do not properly affect the liquid hydrocarbon for distilling purposes. In order to prevent the detrimental results incident to settling of carbon deposits directly upon the bottom of the still B, a screen 22 is provided, of extremely fine mesh, preferably one hundred or one hundred and twenty meshes to the square inch, which is mounted adjacent the bottom of the still B, so that any carbon within the still B incident to distillation will settle thereon and be held in spaced relation to the surface of the chamber 11. The screen 22 is provided for the entire length of the chamber 11, including the strips 23 at the sides thereof which are provided with openings 23* for receiving the hooks 24* of the screen supporting members 24. The mem-

bers 24 are disposed longitudinally on each side of the chamber 11, a screen receiving member 24 upon one side being held in spaced relation by means of a connecting rod 25^a with respect to a screen supporting member 24 upon the opposite side of the chamber 11, and substantially as is illustrated in Figure 2 of the drawings. The members 24 are preferably welded or otherwise secured 10 to the still B; and the rods 25^a extend beneath the screen 22 and transversely thereof for supporting the same, preventing any contact thereof with the bottom of the still B. The screen 22 may be readily detached from 15 the hooked ends 24^a for cleaning purposes.

The reflux condenser or vapor tower D is of novel formation, and has been provided for the dual purpose of condensing the heavier fraction in the vapor arising from the 20 still B, and for preheating of a supply of crude hydrocarbon material for the still B. The reflux condenser D comprises a cylindrical case container 25 which is vertically positioned, having the bottom wall 26 thereof provided with an opening 27 adapted to receive an inlet end of the vapor line 28. The container 25 is preferably so positioned 25 above the still B that the vapor line 28 inclines upwardly from the still B to the reflux condenser D. As is well known, the vapor line 28 communicates the chamber 11 of the still B with the chamber 29 of the reflux container 25 for the supply of hydrocarbon vapors to said chamber 29 after the 30 destructive distillation of the hydrocarbon material within the still B. The container 25 is vertically positioned, and the top wall 32 thereof is preferably provided with a man hole 33, whereby access may be had to the 35 chamber 29 for cleaning purposes. A pipe line 34 leads from the container 25 adjacent the top wall 32; said line 34 preferably being vertically positioned for leading the lighter fraction from the container 25 to the condenser E, as will be more particularly set 40 forth hereinafter. A valve 35 is preferably positioned within the line 34 adjacent its connection with the container 25 for regulating purposes. Since the reflux condenser 45 chamber 29 is of necessity in communication with the chamber 11 of the still B, considerable pressure will exist in the chamber 29, and to prevent liability of accident a safety valve 37 is provided in the container 25 upwardly thereof.

A line 40 for the supply of crude hydrocarbon materials enters the reflux condenser chamber 29 from the top wall 32, and a portion 42 extends downwardly in straight line 60 manner through the chamber 29 to a point adjacent the bottom wall 26. From this point, the pipe line 14 spirals upward within the chamber 29 in a plurality of convolutions 44 to a point adjacent the top wall 32. 65 From this point, a portion 45 of the line

40 extends downwardly through the chamber 29 and diametrically opposite to the portion 42, said portion 45 extending through the bottom wall 26, as at 47. From the point 47, the line 40 leads to the still B, 70 and extends downwardly through the top thereof, having an outlet end 48 adjacent the screen 22 of said still B. A cut off valve 49 may be provided in the line 40 immediately adjacent its connection with the still B. The line 40 has a pressure pump 50 in communication therewith for the purpose of forcing hydro-carbon products therefrom through the reflux condenser D and into the still B, cooperation with the improved process in a manner which will be 75 subsequently described.

A back run line 52 is provided, connected at its upper end to the lower end of the pipe line 34; said line 52 being preferably 80 inclined from its connection with the line 34 to enter the rear plate 19 of the still B; and is downturned within the chamber 11 of the still B to have an outlet 54 directly over the screen 22. This back run line 52 is provided 85 for receiving condensed fractions of higher boiling point which condense within the line 34 intermediate the reflux condenser D and condenser E. A valve 55 is preferably provided in the vapor line 34 intermediate the 90 connection of the back run line 52 therewith and its connection with the condenser D; said valve 55 being either of the automatic or manually controlled type. The condenser E is of any preferred type and is provided 95 for the well known purposes of condensing the lighter and more volatile fractions. The resultant hydro-carbon products flow from the condenser E through a line 57 into the gas separator F, where the volatile fraction 100 in liquid form is separated from the "fixed" or dry gases, and led through a line 59 to the liquid storage tank G. The "fixed" or dry gases exit from the gas separator F through a line 58, and may be 105 directed through a line 60 into the gas fuel storage tank H. A valve 61 is preferably provided in the line 57 intermediate the condenser and separator. A valve 62 may also be provided in the liquid flow line 59. A 110 meter 64 may also be provided in the line 59 for registering the number of gallons of the volatile gasoline distillate entering the storage tank G. A cut off valve 64^a may be provided in the gas exit line 58. Since in 115 some instances it will be desirable to lead the dry gases from the separator F to a location other than the storage tank H, the line 58 is continued beyond the connection of the tank line 60 therewith; a valve 67 120 being provided in this line 58, normally being closed in order to direct the fixed or dry gases into the storage tank H. A control valve 68 may likewise be provided in 125 the tank line 60. Pressure valves 70 and 71 130

may be provided on the gas separator and gas storage tanks respectively, as may also any accessories which are needed, such as a liquid gauge 73 upon the gas separator 5 tank F.

An important feature of this invention resides in the fact that the dry gases may be conveyed by a line 75 to the fire box 10 of the furnace C, for supplying a fuel to the 10 furnace C. A valve 76 may be provided for the line 75 for regulating the flow of gas therethrough.

A drain line 77 is provided, having communication at one end with the still B so 15 that cylinder stock residuum may be withdrawn from the chamber 11 and passed through the cooling box K. Suitable expansion joints 78 may be provided in the line 77, as may valves 79 also be provided 20 in lines 77 adjacent the still and cooling boxes respectively.

In operation, the initial supply of crude hydrocarbon material enters the still B through the storage line 12 until a predetermined quantity has entered as indicated 25 by the meter 14. The valves in all of the pipe lines communicating with the still B, with the exception of the vapor line 28, are then closed and after heating of the still B 30 by products of combustion from ignition of the fuel emanating from the gas line 75, until destructive distillation occurs within the chamber 11, vapors arise into the vapor line 28 and are conveyed into the chamber 35 29 of the reflux condenser D. The initial supply of hydrocarbon materials in the chamber 11 will be diminished by vaporization and the flow thereof to the vapor line 28, so that in order to make the process 40 continuous, it is necessary to have a continuous flow of crude hydrocarbon material into the chamber 11 of still B. This crude hydrocarbon material is supplied through the line 40 above described, the same being forced by 45 pumps 50 therethrough in volume indicated by the meter 80. This supply of hydrocarbon products in the line 40 is unheated and will pass downwardly into the portion 42 of the line 40 within the chamber 29, and upwardly through the coil convolutions 44, said material within the line 40 making its 50 exit through the downwardly extending pipe portion 45 for flow into the still B. Since the vapors entering the chamber 29 55 from the vapor line 28 are extremely hot and even under pressure, it is obvious that the heavier fraction of the vapor products will condense within the chamber 29, due to contact against the cooling surface of the portions 42, 44 and 45 of the pipe line 40 therein, this heavier fraction of the hydrocarbon vapor after condensation dropping within the chamber 29 for return to the still 60 chamber 11 through the vapor line 28. The reflux condenser D thus serves a dual func-

tion in that the heavier fraction is condensed from the vapors in the chamber 29, as is also the crude material flowing through the pipe line 40 preheated within the chamber 29, prior to its flow into the still B. It is an 70 important feature of the reflux condenser D that the vapors are entirely separated from any contact directly or indirectly with respect to the crude hydrocarbon liquid passing through the pipe line 40. The advantage 75 of such arrangement lies in the fact that there can be no association of the vapor and liquid molecules to the detriment of the lighter fraction passing through the chamber 29. The lighter fraction, which has not 80 been condensed, then passes through the line 34 on its way to the condenser E. However, some of the lighter fraction will be condensed within the line 34 and will return to the still B through the run back line 52 as 85 above mentioned. The vapor products entering the condenser E are treated therein in the well known manner, so that the more volatile fraction is condensed and after passing through the line 57, the gas and liquid 90 constituents are separated and disposed respectively in the tanks H and G.

From the foregoing, it can be seen that a process for the refining of hydrocarbon materials has been provided, which while simple in operation is a continuous process, and will permit of operation over a relatively long period of time without undue deterioration or detrimental effect to any particular unit in the apparatus by which the process is effected. The screen 22 is an important 100 feature of this invention, in that the same will only permit vapor and hot oil to pass therethrough, and will catch and hold any carbon that settles thereon due to decomposition of the hydrocarbon material within the still B. In this manner, the life of the still B is prolonged far beyond the life of the ordinary still used in the distillation of hydrocarbon materials.

Various changes in the shape, size and arrangement of parts may be made to the form of the invention herein shown and described, without departing from the spirit of this invention or the scope of the claims.

I claim:

1. In an apparatus for refining hydrocarbon materials the combination of a still, means for supplying a hydrocarbon material to the still, a reflux condenser, means communicating the lower end of the reflux condenser with the still, a coil within the reflux condenser, an inlet conduit leading upwardly within the reflux condenser from the bottom of the coil and existing from the reflux condenser at the top thereof, and an exit conduit connected to the top of the coil and leading downwardly through the reflux condenser and existing through the bottom of the reflux condenser and leading into said 120 125 130 135 140 145 150 155 160 165 170 175 180 185 190

still and having an outlet adjacent the bottom of the still.

2. Apparatus for the refining of hydrocarbon materials comprising a still, a screen
5 carried within the still at the bottom thereof, means for heating said still along said bottom of the still, a condenser, means between the condenser and the still for conveying vapor from the still to the condenser
10 including a condenser, means for passing a fresh supply of hydrocarbon through said

second mentioned condenser on its way to said still, said last mentioned means having an outlet for the fresh supply of hydrocarbon at the bottom of said still just above the 15 screen therein, and a run back line connected between said first and second mentioned condensers for conveying condensed liquid to within the still at a point adjacent the bottom of the still just above the screen 20 therein.

FRANK M. FLOYD.
